CONTAINER OPENING KEY

John M. Hothersall, Brooklyn, N. Y., assignor to
 American Can Company, New York, N. Y., a
 corporation of New Jersey

Application June 23, 1933, Serial No. 677,331

1 Claim. (Cl. 220—52)

This invention relates in general to key opening sheet metal containers and has more particularly for its object the provision of an improved opening key for expeditiously removing a tearing strip or area from a wall of a container to open the container and permit its being emptied.

The principal object of the invention is the provision of an improved key for effectively removing a tearing strip or tearing area defined by 10 a score line or score lines in a wall of a sheet metal container, the key being adapted when in a vertical position, to first puncture the strip or area at a fixed point adjacent the score line, and adapted, when in a horizontal or pivotal position, 15 to have separate means insertable in said puncture so that pivoting of the key initially breaks through the container wall on the score line and further pivoting or rotation of the key severs the metal at the base of the score line and winds 20 off the strip or area upon the key.

An important object of the invention is the provision of an improved opening key having a shank which, when held in a vertical position, is adapted to produce a puncture adjacent a score 25 line and having also a transversely extending part which, when the key is held in a horizontal position is adapted to enter said puncture and break the metal of a container wall beneath said score line to more easily start the tearing of 30 the metal at an exact position on the score line.

A further object of the invention is the provision of an opening key for a scored container, which is inserted into an exact position relative 35 to the score line and which first breaks through the score line by utilizing a short leverage, giving easy initial tearing of the metal, the key thence utilizing a longer leverage for more rapidly winding the removable area on the key as the container is opened.

Still another object of the invention is the provision of such an improved key adapted to produce an initial puncture of the tear away area while held in vertical position, in which position the weight of the operator's hand can best 40 be utilized for effecting an easy puncture.

Numerous other objects and advantages of the invention will be apparent as it is better understood from the following description, which, taken in connection with the accompanying drawing, 45 discloses a preferred embodiment thereof.

Referring to the drawing:

Figure 1 is a perspective view of a container and a key embodying the present invention and illustrating the initial tearing of the score line 50 in the opening operation;

Fig. 2 is an enlarged sectional detail taken through the container (without the key) at a position indicated by the line 2—2 in Fig. 1, this view showing a part of the score line and a fixed depressed point adjacent the score line where the initial puncture is produced;

Fig. 3 is a view similar to Fig. 2, illustrating the sharp point of the key shank puncturing the tearing area adjacent the score line;

Figs. 4 and 5 are views similar to Fig. 3, illustrating the transverse lug extension of the key shank in different opening positions;

Fig. 6 is a perspective view of the key shown in Fig. 1, as seen from its top; and

Fig. 7 is a view similar to Fig. 6 showing the key 15 as it looks turned upside down.

To illustrate a preferred embodiment of the present invention, the drawing disclose a sardine container of the roll top type, having a drawn body 11 and a cover or top 12 secured in any 20 suitable manner as by a double seam 13. The top 12 is countersunk and comprises a flat panel having a removable area 14 set off by a score line 15, which is cut partially through the wall of the cover. A plurality of defined key inserting or 25 puncturing positions (two being illustrated) are set off in the removable area 14 of the cover wall by depressions 16, (Figs. 1 and 2), at the base of which the metal may be weakened. These depressions are located at a predetermined dis- 30 tance from the score line 15 adjacent the ends of the container and just within or inside of the score line.

An opening key 21 (Figs. 6 and 7) is formed (preferably blanked from a single piece of suitable sheet metal) with a finger engaging, oblong, head 22, having a centrally located circular perforation 23, which permits the key to be strung on a wire or hung on a nail. The key 21 is provided with a shank 24, bent to provide spaced 40 parallel side walls or flanges 25 and 26 joined by a connecting wall or back 27.

The flanges 25 and 26 terminate longitudinally at 28 and 29, and the back wall 27 terminates into a triangular puncturing spear 31, having its ex- 45 tremity tapered into a sharp cutting point 32.

A laterally extending arm or lug 33 is formed on the shank, between the point 32 and the flange 25, as an integral part of the back 27 and the flange 25. This lug is slightly curved as shown 50 and its peripheral edge is blunt and rounded.

In opening the container the key is held in vertical position (Fig. 3), with the sharp point 32 engaging the center of the depression 16, and with the flanges 25 and 26 pointing away from 55

the nearest end of the container. With the thumb, index and middle fingers gripping the shank 24 and with the head 22 firmly pressed against the palm of the hand, slight downward pressure exerted by the hand of the operator will force first the sharp point 32 and then the whole spear 31 through the bottom of the depression 16, which may or may not have been weakened by scoring, until further penetration of the spear 31 is stopped by the transverse lug 33 and the flange 26.

The key is then withdrawn vertically, and the curved lug 33 is inserted in the opening created by the spear 31. The key is now in edgewise, horizontal position with the lug 33 pointing towards the bottom of the container. A clockwise quarter turn of the key brings the lug 33 into the position shown in Fig. 4, with the rounded, blunt edge of the lug directly under and in alignment with the score line 15. Further turning of the key forces this edge upwardly, tearing the metal underneath the score line for an initial breaking of the score as illustrated in Fig. 1. The length of the lug 33 determines the leverage of the key in this initial tearing movement, and this being relatively short, makes an easy opening or severing through the container wall.

Further rotation of the key brings the edge of the flange 26 against the top wall of the tearing area 14 (Fig. 5) and this edge thereupon be-

comes the fulcrum on which the key further pivots. The metal of the removable area 14 engaged by the lug 33 is thus bent back and is finally wound upon the key during its continued rotation. The leverage of the key beginning with its fulcruming movement just described is substantially twice the leverage utilized by the lug 33 in the initial severing. This increases the rapidity with which the removable area 14 is torn away along the score line 15, the latter tearing much easier after it has been initially broken.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

A key for opening cans, constructed of sheet metal substantially U-shape in cross-section, the median web of said key terminating in an axially aligned can-puncturing element, one of the side flanges of the key having a lateral extension for engagement with the opening made by said puncturing element to remove a portion of the container by a rolling movement of said key.

JOHN M. HOTHERSALL. 30
